GAS-FUELED FIREPLACE LOG

Raymond R. Dupler, 744 Euclid St., Toledo, Ohio
Original No. 3,113,611, dated Dec. 10, 1963, Ser. No. 793,388, Feb. 16, 1959. Application for reissue Dec. 8, 1964, Ser. No. 431,238

4 Claims. (Cl. 158—100)

Matter enclosed in heavy brackets **10** appears in the original patent but forms no part of this reissue specification; matter printed in italics indicates the additions made by reissue.

This invention relates to a foraminous casting and method of making same.

The production of a foraminous metal casting has been a difficult and expensive ordeal, particularly when a large quantity of small holes are required. This problem manifests itself for example in making a cast metal fireplace log or the like where a great many of very small holes are necessary for the escape of the air-gas mixture. To drill all of these holes is so expensive as to be virtually prohibitive. It is therefore a desideration to produce a metal casting which can be provided economically with holes of the desired size and appropriately arranged, concomitant with the casting step so that when the casting has cooled, the desired foraminous structure is produced without further work.

Objects of this invention are to produce a new and improved foraminous casting and method of making same which satisfactorily cope with the problem above recited.

Other objects and advantages of the invention will hereinafter appear and for purposes of illustration but not of limitation, an embodiment of the invention is shown in the accompanying drawings in which

FIGURE 1 is a front plan view of a fireplace log;

FIGURE 2 is a rear elevation of the fireplace log shown in FIGURE 1;

FIGURE 3 is a transverse sectional view of the fireplace log shown in FIGURE 1;

FIGURE 4 is an enlarged fragmentary section of a portion of the face of the fireplace log showing one of the ceramic inserts; and

FIGURE 5 is a transverse sectional view substantially on the line 5—5 of FIGURE 4.

The illustrated embodiment of the invention comprises a gas fireplace log structure **10** which for example may be made from a gray iron casting and is shaped at the front to simulate a pair of wooden logs **11** arranged one above the other in stacked formation. As shown in FIGURE 2, the back of the log structure has suitable upright end supporting angle irons **12** and bottom angle irons **13**, these being joined by a transverse angle iron **14**. Also in the rear and at the lower part of the structure is the horizontally disposed gas admission pipe **15** which has a pair of upwardly extending branch pipes **16**. The usual air mixer **17** is disposed between the outer end of the pipe **15** and a regulating valve **18**. The branch pipes **16** lead respectively to a pair of horizontally disposed gas plenum chambers **19** directly in rear of the gas emitting surface in the simulated logs. In the front wall of each of the plenum chambers is a large number of small orifices **20** through which the gas-air mixture passes to be ignited.

In accordance with this invention the orifices **20** are formed by a plurality of relatively small ceramic tubes or inserts **21**, the rear end of which open into the respective plenum chambers and the front end of which open to the outer surface of the log. The size of the orifices **20** may be varied as desired but for the purpose intended may be of the order of $\frac{1}{16}$ of an inch in diameter. The length

2

of the inserts may vary according to the wall thickness of the casting but may be of the order of $\frac{1}{2}$ of an inch and the overall diameter of the inserts may be of the order of $\frac{3}{16}$ of an inch. Manifestly these dimensions are only approximate and not critical and will depend upon the wall thickness of the casting.

It is necessary that the inserts have sufficient mechanical strength so as not readily to be broken or fractured. However, it is important that the inserts **21** be of a suitable material, such for example as porcelain, having a melting or fusing point substantially in excess of that of the casting. Thus, the inserts are arranged in the desired manner in the mold and the molten metal cast around them. If the melting point of the insert is not sufficiently high, it will melt or fuse and close the passage **20**, and thus materially restrict escape of gas and air from the log. Thus, it is necessary to determine the melting point of the metal employed for forming the fireplace structure and then select a material for the inserts which will not adversely be affected by the heat of the molten metal as it is being cast.

From the above it will be apparent that the fireplace log structure can be readily produced to effect the desired porosity quickly and efficiently and at a minimum of expense, thereby avoiding the high expense of individually drilling the holes to effect the desired foraminous structure.

As used in the claims, the expression "ceramic" is to be used in its broadest sense to connote any material which has a fusing temperature sufficiently above that of the cast metal so that the metal may be cast in a mold in which a plurality of the inserts **21** have been previously arranged without melting or distorting them to such an extent as to render them useless for the purpose intended.

Numerous changes in details of construction and choice of materials may be effected without departing from the spirit of the invention especially as defined in the appended claims.

What I claim is:

40 1. A gas fireplace log and the like comprising a cast metal body, the outer surface of said body simulating the appearance of the surface of a wooden log, a gas plenum chamber disposed within said metal body and adjacent said outer surface, a plurality of orifices arranged in spaced relationship over said outer surface of said body, each of said orifices comprising a short tubular member of relatively higher melting point than said metal body, said tubular member being embedded in said cast metal body during the casting thereof and providing communication between said outer surface and said plenum chamber.

45 2. The gas fireplace log of claim 1 wherein said tubular member is composed of a ceramic material.

50 3. The gas fireplace log of claim 1 which also comprises means for supplying a combustible gas to said plenum chamber.

55 4. A device of the character described comprising a cast metal body having an outer irregular surface and an inner surface, a plurality of orifices randomly arranged in spaced relationship over said outer surface of said body, each of said orifices comprising a short tubular ceramic member of relatively higher melting point than said metal body, said tubular ceramic member being embedded in said cast metal body during the casting thereof and providing communication between said outer surface and said inner surface.

60 5. The device of claim 4 wherein the outer surface of said body is irregular.

65 6. The device of claim 4 wherein the inner surface of said body is irregular.
